SPEED CONTROL FOR VEHICLES

Sidney S. Pulaski, Milwaukee, Wis.

Application February 7, 1940, Serial No. 317,636

12 Claims. (Cl. 105—61)

This invention relates in general to improvements in speed control means for vehicles but is concerned more particularly with an arrangement for controlling the operation of toy vehicles, for example, and the principal object of the invention is to provide means whereby the speed of a vehicle is controlled in accordance with centrifugal or gravitational forces acting upon the vehicle during its passage over a path of travel including straight, curved, and graded sections.

A further object of the invention is to provide means for automatically controlling the speed of a vehicle when it enters a curved section of the path of travel or when a down-grade is encountered.

Another object is to provide a speed control arrangement for a vehicle in which centrifugal or gravitational forces are effective to slow up the speed of a vehicle when it enters a curved section of track and is caused to swerve or where it encounters a down-grade, so that derailment of the vehicle is prevented.

A further object of the invention is to provide a centrifugal or gravitational actuated speed control in which the effective control point is universally adjustable in order to compensate for various curvatures or elevations of track sections.

An additional object of the invention is to provide a novel vehicle speed control arrangement which can readily be applied to new or existing vehicles, which is of simple construction, is easy to install and also is economical to manufacture.

The invention in its essence is applicable to the operation of toy electric railroad trains and consists primarily of a mercury contact tube or switch having a globule of mercury therein, arranged within the body of the toy locomotive in such a manner that the movement of the train along a section of track when a curve is encountered, for example, forces the globule of mercury by centrifugal force against the mercury contact electrodes to complete a circuit which is effective to reduce the speed of the vehicle. The mercury tube is arranged to be universally adjusted so as to provide for any degree of track curvature.

In the operation of toy electric railroad trains it is customary to provide a transformer box having a tapped secondary winding whereby the speed of the electric train may be conveniently regulated manually. In the operation of such an arrangement the person operating the switch on the transformer box must carefully watch the position of the train upon the track so that the train may be speeded up on the straight sections

of track and slowed down when curves or down-grades are encountered, in order that no derailments may occur. Ordinarily a person operates the train at the slowest speed possible at which the train can be run without derailment at the curves. This is not altogether satisfactory since a locomotive is not able to pull a large number of cars at the slow speed, and furthermore the child or person operating the train derives greater enjoyment therefrom when the trains are operating at a higher speed. When the trains are operating over the track at high speed numerous derailments occur at the curves in the track as is well known, causing considerable damage to the vehicle and track, and necessitating frequent expensive repairs as well as the danger of a child receiving electrical shocks in replacing the vehicle upon the track. It will be appreciated that the invention is applicable to vehicles whose travel is not confined to a track, but which travel freely in any direction indiscriminately.

In accordance with the foregoing the principal object of the invention is to eliminate the foregoing disadvantages and provide a speed control arrangement for an electric train in which the speed of the train can be very high on the straight sections of track while upon curvatures or down-grades the speed is greatly reduced automatically without the necessity of manually regulating the speed from the transformer box. Derailment of the train is thereby reduced and the life of the equipment is considerably extended.

Other objects and advantages not particularly pointed out reside in certain novel features of the elements, parts and construction thereof as well as their association and cooperation. These will be apparent and pointed out more specifically in the accompanying description of the invention which, taken together with the drawing discloses a preferred embodiment including several modifications thereof, of the present invention. In the drawing:

Fig. 1 discloses a cross-sectional elevation of a vehicle such as a locomotive showing the invention applied thereto;

Fig. 2 is an end view of the vehicle and control therefor;

Fig. 3 is a schematic circuit diagram illustrating the principles of operation involved in the invention;

Fig. 4 is a modification of the speed control device showing a mercury switch for enabling a vehicle to operate in either of two directions;

Fig. 5 is a modification of the speed control

device in which a weighted member is utilized to control the speed of the vehicle; while

Fig. 6 illustrates a track section arranged for one of the adaptations of the invention.

5 Referring now particularly to the drawing the reference character 5 discloses a conventional vehicle such as a stream-lined toy electric locomotive of well known construction formed of stamped sheet metal, for example. The propelling or 10 motive power for the vehicle is indicated generally at 6 and comprises the well known universal A. C.-D. C. series wound electric driving motor supported and carried between a pair of frame members 7. The supporting members 7 have a 15 bracket 8 attached thereto at the top through which a screw bolt 9 is threaded for supporting the electric motor within the locomotive body 5. The driving wheels 10 and 11 for the vehicle are journaled in supporting members 7 and geared 20 to the electric motor 6 at the opposite side of the motor (not shown). A truck 12 carrying a set of wheels is arranged at the rear end of the locomotive body and is pivotally supported to a platform 13 riveted to the sides of the body 5, as 25 shown.

The electric motor 6 includes the commutator segments 14 upon which the motor brushes 15 and 16 are adapted to bear. The brush 15 has a metal tab 17 connected to it which at the other 30 end is clamped by the screw 18 threaded into the metal supporting member 7, whereby the brush 15 is grounded on the member 7 through the tab and screw 18. The brush 16 is provided with a metal tab 19 for connecting electric wires thereto. 35 Both the brushes 16 and 17 are supported upon an insulated strip 20, suitably secured to the supporting member 7 at each end as shown.

The electric propelling motor 6 is provided with the usual series field winding 21 and a number 40 of armature windings 22, usually 3. A portion of the magnetic field core for the motor 6 is indicated at 23. A variable resistor is provided for regulating the reduced speed at which the vehicle is to traverse the curved or down-grade 45 sections of track. It comprises an appropriate number of turns of a resistance wire 24 wound upon a curved insulating strip 25, which in turn is secured by screws at each end to the supporting member 7. An adjustable wiper arm 26 50 pivoted at 27 to the member 7 is provided with a projecting tab 28 for manually adjusting the position of the arm 26 across the resistance 24 at any desired point.

The electrical connections for the electric motor 6 extend over wire 29 from one side of the field winding 21 to the tab 19 and brush 16, while the other side of the field winding 21 extends by way of wire 30 to the usual collector brush 31 arranged near the bottom of the vehicle in 60 contact with the center rail of the track system.

The means for controlling the speed of the vehicle or locomotive by centrifugal force is shown here in the form of a mercury switch comprising a glass tube 32 of well known construction. The mercury tube 32 is carried upon an 65 adjusting arm 33 arranged within the vehicle and projecting through the top thereof. The arm 33 has a pair of spring clips 34 riveted thereon for securely gripping the mercury tube. The mercury tube 32 is provided with the usual globule 70 of mercury 35 which is adapted to move longitudinally within the tube 32 from one end to the other by either centrifugal or gravitational force. As shown in Figure 2, the mercury 35 is 75 normally resting in the left hand portion of the

tube 32 by action of gravity due to the tilted position of the tube. When the mercury moves over to the right hand end of the tube it establishes an electrical contact between a pair of electrodes 36. One of the electrodes 36 is connected by flexible wire 37 with the resistance coil 24, while the other electrode is connected by flexible wire 38 with the brush tab 19.

With the lever arm 33 in the vertical position as shown in Figure 2, the mercury tube 32 is normally tilted as shown so that the mercury globule 35 rests in the left hand end of the tube or away from the electrodes 36. As long as the train proceeds over a straight section of track this condition prevails. However, in the event that the 10 train enters a section of track which is curved in the left hand direction for example, then the globule of mercury 35 is thrown by centrifugal force across the length of the mercury tube 32 into engagement with the electrodes 36 and an 15 electrical circuit is established therebetween. Should the track section be arranged so that the curvature thereof extends in the right hand direction, the adjusting lever 33 must first be adjusted so that the mercury switch 32 is reversed 20 25 180° or change ends from that shown in Figure 2.

The foregoing adjustment is provided for by arranging the adjusting lever 33 to be universally pivoted as by a bolt 39, whose tension is maintained as by spring washers so that the lever 33 30 will remain stable in its adjusted position. The lever pivot 39 and lever 33 are in turn supported upon an angular bracket 40 which is also pivotally secured to the locomotive platform 13 by a bolt 41 whose tension is maintained by spring 35 washers to hold the adjustment stable. From the foregoing it is seen that the combination of the bolts 39 and 41 enables the adjusting lever 33 to be universally adjusted so that the tube 32, as viewed in Figure 2, may be tilted more or less to the right or left by the lever 33 pivoting about bolt 39 to adjust the control point at which the electrodes 36 are to be closed. By turning the lever 33 axially 90° about pivot bolt 41 the tube 32 is positioned parallel to the track section and 40 the locomotive so that the globule of mercury in the tube 32 is effective by gravitational pull to roll along the length of the tube 32 and establish contact between electrodes 36 when a down-grade 45 section of track is encountered. By rotating the lever 33 180° from the position shown in Figure 2 the mercury tube 32 is adjusted to effect its control when right hand turns are made by the locomotive. It will be likewise apparent with the 50 foregoing adjustments that any desired intermediate position between the aforesaid positions or any other position in which it is desired to tilt the tube to establish a particular control point, may be readily accomplished by this universal arrangement. While all of the foregoing adjustments are conveniently made by the lever 33 55 extending through the top of the locomotive it may be more convenient to provide a lever arm 42, shown in Figure 2, and attached to the angular bracket 40 for adjusting the axial positions of 60 the mercury tube 32.

The wheels 10 and 11 of the locomotive and the truck 12 are adapted in the usual manner to ride upon a pair of rails 43. These rails 43 serve to carry the feed circuit to the grounded side of 70 the electric motor 6, while the center rail 44 is adapted to be wiped over by the collector 31 carried below the locomotive carriage.

In Figure 3 there is illustrated a circuit diagram depicting in diagrammatic form the various 75

elements concerned with the invention and the novel circuit arrangement thereof. The usual current feeding transformer 45 is provided, having its primary winding connected by wires 46 and 47 to a source of relative high voltage, such as 110 v. 60 cycles, for example. The secondary winding of transformer 45 are suitably tapped, as shown, at 48 and the taps are adapted to be engaged at various points by the manual adjustable control arm 49. It is customary in some of the more modern toy electric locomotives to provide means for reversing the direction of travel of the locomotive while it is on the track. This may take the form of either an automatic control 10 or a manual reversing switch such as that indicated at 50, which is arranged upon the locomotive 5 in any accessible position.

In the operation of the control arrangement current is normally fed from the tapped transformer secondary winding 48 to the center feed rail, and from the manual speed control arm 49 to the outside rails 43. From here the current passes along the outside rails 43 through wheels 10 and 11 of the locomotive 5 and from there 15 through the supporting member 7 to the screw 18 and motor brush 15 by way of reversing switch 50. A branch of this circuit extends from the member 7, pivot 27 and wiper arm 28, and the resistor winding 24 to the wire 37 and then to 20 one of the electrodes 36. The other side of the circuit extends from the center third rail 44, through collector brush 31, wire 30, the motor field winding 21 and the wire 29, by way of reversing switch 50 to the brush 16. A branch of 25 this circuit extends from the tab 19 over wire 38 to the other one of the electrodes 36. The motor 6 is energized in the well known manner by current passing through the field winding 21, the brushes 15 and 16, commutator 14 and the armature windings 22. This action operates the 30 motor 6 and propels the vehicle or locomotive in either a forward or backward direction along the track depending upon the position in which the reversing switch 50 is thrown. The speed of the 35 locomotive, of course, is dependent upon the number of taps 48 of the secondary winding of transformer 45 included in the circuit and the locomotive quickly reaches the speed at which the arm 49 is set for. This speed is maintained 40 constant as long as a level section of track is traversed by the locomotive. However, as soon as a curved section of track or a down-grade is encountered, depending on the manner in which the lever arm 33 is adjusted, the mercury globule 35 in the tube 32 is immediately thrown by 45 centrifugal force or flows by gravitation along the tube until it encounters the electrodes 36. The mercury globule 35 remains in this position 50 as long as the curved track or down-grade portion is being traversed by the locomotive. Accordingly, a shunt circuit path is established extending over flexible wires 37 and 38 from the electrodes 36 through the variable resistor 24 and its wiper arm 28, in series with the field 55 winding 21 and in parallel with the circuit extending through the motor 6 and across the tracks 43 and 44. This shunt circuit around the armature windings 22 is effective to greatly 60 reduce current feed to the windings 22 thereby quickly effecting a considerable reduction in the speed of the locomotive. At the same time the current passing through the field winding 21 is 65 proportionally increased which is effective to greatly increase the magnetic flux passing through the core 23 and thereby act as a mag-

netic brake upon the commutator 14. As a result the speed of the train is automatically reduced until the locomotive again approaches a straight or level section of track whereupon the globule of mercury 35 moves out of engagement 6 with the electrodes 36 and the aforesaid shunt around the armature windings 22 is removed. The speed of the train is accordingly quickly increased. In order to properly regulate the amount of the reduced speed at which the train 10 is to negotiate the curves or down-grades the wiper arm 28 can be variably adjusted across the resistor 24 to introduce more or less resistance in the shunt circuit of the motor.

Instead of providing a shunt circuit around 15 the motor armature windings 22 to reduce the speed of the vehicle it is readily conceivable that the same results may be accomplished by connecting the shunt circuit controlled by mercury switch 32, across the field winding 21. In this 20 arrangement the current through the armature would be greatly increased when the switch 32 operated while the current through the field winding 21 would be considerably reduced and the net result upon the motor 6 would be to 25 immediately reduce the speed.

An advantage derived from the arrangement of the invention beside making the standard curves and elevations more practical is that the number of curves of a typical track layout may 30 be greatly increased and the radius of curvature may be considerably shorter than is at present practical, resulting in a saving of trackage and space and providing for more spectacular and interesting train track layouts.

While the arrangement as disclosed in the drawing is applicable for a train traveling in a forward direction and one in which the mercury tube is adjusted to effect its control of the train only as it negotiates a left hand turn, it will be 40 apparent that it is desirable to provide an arrangement in which either right or left hand turns may be traversed by a train and which may be traveling in either a forward or a backward direction. A modification of this invention, shown in Figure 4, is adapted to accomplish this. This figure discloses a curved-shaped mercury tube 58 adjustably supported on the adjusting arm 33 and which has a globule of 45 mercury 59 normally resting in the lower curved portion of the tube 58. Electrodes 60 and 61 are arranged upon opposite ends of the tube 58 and are electrically connected in parallel with each other to the wires 37 and 38. With this arrangement it is clearly obvious that the centrifugal force acting upon the train negotiating either a right or a left hand turn will throw the mercury globule 59 against either electrode 60 or 61 to effect the reduction in speed of the locomotive. With this arrangement it will be obvious likewise that the train can be run either backwards or forwards on the track and be slowed down at the turns. It is conceivable that if desired a pair of tubes such as 32, illustrated in 50 Figure 2 may be provided, and oppositely disposed or tilted with respect to one another but arranged parallel therewith, in order to perform the same functions which are adapted to be brought about by the modification shown in 55 Figure 4.

In Figure 5 there is illustrated a further form of the invention in which instead of providing a mercury tube to control the speed of the train a weighted member and a set of contacts con- 60 65 70 75

trolled thereby, performs this control function. The control arrangement indicated generally at 51 comprises a flexible leaf spring or rod 52 carrying an adjustable weight 53 at its lower end and secured at its other end in a spring pile-up by means of the screws, as shown. A pair of leaf springs 54 and 55 having contacts on their ends are arranged on one side of the leaf spring 52, while a similar set 56 and 57 are arranged on the opposite side. This spring arrangement 51 is located within a locomotive and may be suitably supported and arranged for various angular adjustments by means of a lever such as 33. When mounted vertically so that the weight 53 hangs downward and with the springs 54 and 55 extending towards the left hand side of the locomotive and springs 56 and 57 on the right hand side, the weight 53 will be swung by centrifugal force either to the right hand side or the left hand side, carrying the leaf spring 52 with it as the train negotiates left or right hand turns. Similarly if the leaf springs 54 and 55 are arranged vertically and facing toward the rear of the locomotive and the leaf springs 56 and 57 towards the front end of the locomotive the spring 52 carrying the weight 53 will be swung forward as the train encounters down-grades. However, since the weight would also engage either the leaf springs 54 and 55 when moving up an incline or upgrade it is more practical to provide only a single set of leaf springs, since it would not be desirable to slow down the speed of the train as it travels up-grade. When the spring set is supported horizontally within the vehicle centrifugal forces are adapted to act upon the weight 53 to effect the speed reducing control as the vehicle encounters a down-grade. Only one set of springs would be required in this arrangement.

In the practical operation of this device when the weight 53 is swung to the left, for example, by the motion of the locomotive entering a curved section of track the leaf spring 54 is first engaged by spring 52. This establishes a shunt circuit extending from the rail 43 around the armature windings 22 of the motor 6 over a path extending through the spring leaves 52 and 54 the resistance 24 and 24' through the field winding 21 to the other rail 44. As a result the speed of the locomotive is reduced. Should the curvature of the track be more abrupt or the speed of the train be greater than is ordinarily encountered, the weight 53 swings farther to the left until the leaf spring 55 is engaged by leaf spring 54. This completes a shunt circuit around the resistor 24 through leaf springs 54 and 55 resulting in a greatly increased current flow through the resistor 24' so that a greater portion of the current is shunted around the armature winding 22, resulting in a further reduction in the speed of the locomotive. The leaf springs 56 and 57 are connected in parallel with the leaf springs 54 and 55 and therefore perform the same function when the train swerves in the opposite direction and the weight 53 is swung in the right hand direction.

In Figure 6 there is shown a further adaptation of the invention in which a section of track is arranged with the parallel rails 43 bent into a succession of short recurring curves 62. As the train enters this section of track at high speed from a straight section it is caused to sway or weave so that the mercury 35 carried by the locomotive, is thrown by centrifugal force to the

end of the tube into contact with the electrodes 36 and back again. This action is effective to immediately slow down the speed of the train the same as if the train entered a regular curved section of track. This arrangement would be desirable, for example, when a train approaches a road crossing or enters a track section where caution is necessary. The same effect may be produced by providing a section of track with a succession of slightly raised portions on opposite sections of the rails, or alternatively a section of straight track may have one of the rails raised slightly higher than the other rail for a short distance in order to tilt the locomotive sufficient to operate the mercury switch and thereby slow up the train until the level section of track is again traversed. The form of the invention shown in Figure 5 wherein a weighted member is used to control contact sets by gravitational or centrifugal force is likewise applicable to the arrangements pointed out above and need not be described further.

It is apparent from the foregoing that a novel type of vehicle speed control means has been devised in which the speed of a vehicle upon curves or grades is automatically reduced in order to prevent derailment of the vehicle, and that numerous desirable advantages are provided with the arrangement of the invention. Also that the invention is not limited in its utility to toy electric trains, but is equally as well applicable to large vehicles of any kind.

While various embodiments of the invention have been illustrated and disclosed it will be apparent that other adaptations and arrangements or slight modifications thereof may be devised by those skilled in the art, and it will be understood therefore that the invention is not to be limited by the precise disclosures but only by the extent of the scope of the appended claims.

What is claimed is:

1. In a speed control arrangement for vehicles, an electric motor for driving the vehicle, means for controlling the operation of the motor to drive the vehicle at a constant speed as long as the vehicle traverses a straight and level path, and means controlled by centrifugal and gravitational forces for automatically reducing the motor speed when the vehicle swerves from a straight path or encounters a down-grade.

2. In a speed control arrangement for vehicles, an electric motor for driving the vehicle, means for controlling the operation of the motor to drive the vehicle at a constant speed as long as the vehicle traverses a straight and level path, and means for automatically reducing the speed of the vehicle, said means operated by centrifugal force when the vehicle swerves from a straight path, and operated by gravitational force when the vehicle encounters a down-grade.

3. In a speed control arrangement for vehicles traversing a track, an electric motor for driving the vehicle, means for operating the motor to drive the vehicle at a constant speed; a mercury tube switch carried by the vehicle having a globule of mercury therein normally resting at one end of the tube as long as the vehicle traverses a straight and level section of track, electrodes at the other end of the tube connected to said electric motor, means responsive to the vehicle traversing a curved track section or a down-grade for moving the mercury globule into contact with said electrodes, and a resistance con-

nected to the motor by the closure of the electrodes for reducing the speed of the vehicle.

4. In a speed control arrangement for vehicles traversing a track, an electric motor for driving the vehicle, means for operating the motor to drive the vehicle at a constant speed, a mercury tube switch carried upon the vehicle having a globule of mercury therein normally out of engagement with the associated electrodes as long as the vehicle is traversing a straight and level track section, means connecting the electrodes and the motor for reducing the speed of the vehicle when the mercury globule is in engagement with the electrodes, and centrifugal and gravitational forces acting upon said mercury globule to cause engagement of the electrodes when the vehicle traverses a curved or down-grade track section.

5. In a speed control arrangement for vehicles traversing a track, an electric motor for driving the vehicle, means for operating the motor to drive the vehicle at a constant speed, a mercury switch arranged to be normally open as long as the vehicle traverses a straight and level track section, and closed when the vehicle traverses a curved track section or a down-grade, means for causing said mercury switch to be closed, and resistance means connected to the motor responsive to the closure of the mercury switch for reducing the speed of the vehicle.

6. In a speed control arrangement for vehicles traversing a track, an electric motor for driving the vehicle, means for operating the motor to drive the vehicle at a constant speed, a mercury switch carried upon the vehicle and arranged to be open as long as the vehicle traverses a straight and level track section, and closed when the vehicle traverses a curved or down-grade track section, centrifugal and gravitational means acting upon said mercury switch to close the same, means responsive to the closing of the mercury switch for reducing the speed of the vehicle, and means for adjusting the angular position of the mercury switch upon the vehicle to position the mercury switch for operation on any degree of track curvature or down-grade.

7. In a speed control arrangement for vehicles traversing a track, an electric motor for driving the vehicle at a constant speed, a mercury switch carried upon the vehicle and arranged to be open as long as the vehicle traverses a straight and level track section, and closed when the vehicle traverses a curved or down-grade track section, centrifugal and gravitational means acting upon the mercury switch for closing the same, means responsive to the closure of the mercury switch for reducing the speed of the motor and therefore the vehicle, adjustable means on the vehicle for predetermining the reduced speed of the vehicle, and universally adjustable means for angularly adjusting the position of the mercury switch to cause the same to be closed for any degree of track curvature or down-grade.

8. In a speed control arrangement for vehicles traversing a track, an electric motor for driving the vehicle at a constant speed, a mercury switch carried upon the vehicle arranged to be open as long as the vehicle traverses a straight and level section of track, and closed when the vehicle traverses a curved or down-grade track section, centrifugal and gravitational forces acting upon said mercury switch for causing the closing of the same, means for reversing the operation of the motor to cause the vehicle to traverse the track in the reverse direction, said mercury switch

effective to be closed as the vehicle encounters curves and down-grades in the said reverse direction of travel, means controlled by the closing of the mercury switch for reducing the speed of the motor and therefore the vehicle, and means for adjusting the angular position of said mercury switch with respect to the vehicle, to cause the switch to be closed at any desired degree of track curvature or down-grade.

9. In a speed control arrangement for vehicles traversing a track, an electric motor for driving the vehicle at a constant speed, means for reversing the operation of the motor to cause the vehicle to travel in the reverse direction, a mercury control switch carried upon the vehicle and comprising a tube having a globule of mercury therein and a pair of electrodes arranged on each end of the tube, said mercury globule normally resting in the tube between the two pairs of electrodes as long as the vehicle traverses a straight and level track section in either direction of travel, and engaged with one or the other sets of electrodes when the vehicle traverses a right or left hand track curve or encounters a down-grade in either direction of travel, centrifugal and gravitational forces acting upon said mercury switch to cause the engagement of the mercury globule with one of the sets of electrodes, and means connecting the pairs of electrodes with the motor for causing the motor to reduce the speed of the vehicle when the globule of mercury engages either set of electrodes.

10. In a speed control arrangement for vehicles traversing a track, an electric motor for driving the vehicle at a constant speed, a control switch carried upon the vehicle and comprising a weighted spring leaf and a second spring arranged in a contactual relationship therewith, said spring leaves normally out of engagement with each other as long as the vehicle traverses a straight or level section of track and moving in contact with one another when the vehicle encounters a curved section of track or a down-grade, centrifugal and gravitational forces acting upon said weighted spring leaf to cause its contactual engagement with said other spring leaf, means controlled by the closing of the leaf springs to reduce the speed of the motor and therefore the vehicle, and means for adjusting the position of the control switch upon the vehicle to cause the leaf springs to be closed for any desired track curvature or down-grade.

11. In a speed control arrangement for vehicles traversing a track, an electric motor for driving the vehicle at a constant speed, a control switch carried upon the vehicle and comprising a weighted flexible member and a plurality of spring leaves arranged parallel thereto, said spring leaves arranged normally out of contact with each other and the weighted member as long as the vehicle traverses a straight and level section of track, and moving successively in engagement with one another when the vehicle encounters a curved track section or a down-grade, centrifugal and gravitational forces acting upon said weighted member to cause such engagement, and a plurality of resistances connected successively into the circuit of the electric motor by the engagement of the spring leaves and the weighted member for gradually reducing the speed of the vehicle, the number of said resistances effective successively being dependent upon the speed with which the vehicle enters the curved track section or down-grade.

12. In a speed control arrangement for a ve-

- hicle traversing a track, an electric motor, a circuit for the motor for driving the vehicle at a constant speed, a control switch carried by the vehicle, said control switch being normally open as the vehicle traverses a straight section of track and closing by centrifugal force as the vehicle encounters a curved track section, a resistance connected in shunt of the motor circuit by the closure of the control switch for reducing the

speed of the motor, means for adjusting the position of the control switch upon the vehicle to vary the point at which the control switch is closed by the centrifugal force, and means for adjusting the value of the resistance to vary the reduced speed of the motor to any desired amount.

SIDNEY S. PULASKI.
